UNITED STATES PATENT OFFICE.

DENIS O'CONNOR, OF JOLIET, ILLINOIS, ASSIGNOR TO CHARLES G. PEARCE, TRUSTEE,
OF JOLIET, ILLINOIS.

WRENCH.

1,360,672.

Specification of Letters Patent. Patented Nov. 30, 1920.

Application filed October 10, 1919. Serial No. 329,752.

To all whom it may concern:

Be it known that I, DENIS O'CONNOR, a subject of the King of Great Britain, residing at Joliet, in the county of Will and 5 State of Illinois, have invented certain new and useful Improvements in Wrenches, of which the following is a specification.

This invention relates to a wrench adapted for the gripping of polygonal or curved 10 surfaces, and is characterized by a number of features of improvement which will more clearly hereinafter appear. In the present wrench, I have aimed to combine lightness with strength, to devise a construction that 15 is inexpensive to manufacture, and to utilize an adjusting nut which is held in operative position and protected against accidental turning, in a novel manner.

A suggestive embodiment of my invention is illustrated in the accompanying drawing, wherein—

Figure 1 is a side elevation of the wrench; Fig. 2 is a front elevation thereof;

Fig. 3 is a perspective view showing the 25 nut and its associated parts in separated relation; and

Fig. 4 is a longitudinal section through the nut with its associated parts in operative relation therewith.

30 The body or handle of my wrench which is designated as 5 may conveniently be produced from flat metal stock that is subjected to the action of suitable blanking and forming dies so as to shape it transversely 35 in conformity with the letter U, resulting in the formation of a back 6, sides 7, and inwardly turned front edges 8 in the region where the wrench is adapted to be seized by the hand. Near the upper end of the 40 wrench a shoulder 9 projects inwardly to provide a narrower portion 10 immediately adjacent the wrench back, this shoulder extending downwardly from the top for any desired distance. Formed on each side of 45 the wrench near the upper end thereof is a circular boss 11 surrounding a round aperture 12, the apertures in the two sides being alined, and the boss presenting the effect of an outwardly turned flange.

50 The upper end of the wrench may be suitably recessed and formed to receive a fixed jaw 13, preferably serrated as shown, and adapted to coöperate with a movable jaw 14 carried upon the usual shank 15. As appears 55 in Fig. 2, this shank is substantially rectan-

gular in cross section, so as to lie non-rotatably between the side walls 7 of the wrench body. The fixed jaw and shoulder 9 act respectively as front and rear stops for the movable jaw by abutting its shank whenever the jaw is tilted forwardly or rearwardly.

A means of connection and adjustment between the movable jaw and the wrench body is provided in a nut 16 best shown in Fig. 3 which may, if desired, have a knurled finger portion for facilitating rotation thereof. This nut may be of any standard kind, being formed interiorly with threads 17 adapted to coöperate with the threads of 70 the shank so as to effect relative adjustments between the movable and fixed jaws of the wrench. The nut is mounted within the wrench body in a novel manner through the use of companion bearings 18, each of which 75 is slotted as at 19 to receive the shank of the movable jaw. These slots are each flanked with lugs 20 having outer convex faces in conformity with the curvature of the opening within the nut. Each of these 80 bearings, moreover, has its side walls 21 bowed outwardly to project beyond the nut, as appears best in Figs. 2 and 4, so as to protect the nut from contact with a plane surface whenever the wrench is laid down. 85

When the parts are assembled in operative relation, the nut with its associated bearings is placed within the two openings 12, and turned to present the slots 19 in line with the shank of the movable jaw. The 90 bosses 11 constitute a widened seat against which these bearings lie to afford support for the parts which coöperate with the movable jaw, and which are free to rotate within the openings 12 for any required distance 95 as the jaw is tilted forwardly or rearwardly. As already explained, its rearward movement is stopped by the shoulder 9. Normally the movable jaw is held in a forward position to coöperate better with the fixed 100 jaw, as by means of a leaf spring 22 adapted to lie between the walls 7 within the narrow portion 10 immediately adjacent the back 6 of the wrench body, the spring being held in place therein as by means of a rivet 105 or pin 23.

According to the present construction, rotation of the nut will effect longitudinal movements of the movable jaw in the usual manner, but the parts being freely assem- 110

bled within the wrench body are capable of moving as required to permit the jaw to tilt rearwardly, and, when desired, to be readily withdrawn from the wrench body. It will 5 be understood, of course, that I do not desire in this invention to be limited to a wrench body that is formed of sheet metal, although this is a desirable construction, but may, if preferred, form this part otherwise. 10 Also in respect of other features which are susceptible of modification without sacrificing the advantages of my invention, I desire that they should be included within the scope of this patent, all as defined in the claims following.

I claim:

1. A wrench whose body is U-shaped in cross section to provide a back and parallel sides in spaced relation, each side being 20 formed with an outwardly extending circular boss within which is a circular opening in alignment with the other, a fixed jaw mounted on the wrench body and a movable jaw adapted to coöperate therewith having 25 a threaded rectangular shank extended between the sides of the wrench body, and means for effecting adjustments of the movable jaw comprising a nut interiorly threaded to coöperate with the threaded shank, and 30 companion bearings adapted to be rotatably seated within the circular openings in the body sides, and each having a slot for receiving therethrough the shank of the movable jaw, and a pair of lugs with convex outer 35 faces formed adjacent the faces of each slot, the lugs being adapted to enter the opening within the nut to preserve the nut and bearings in axial alignment, substantially as described.
- 40 2. A wrench having a body formed in part of spaced parallel walls, a jaw having a rectangular threaded shank adapted to enter between such walls in each of which adjacent the shank are registering circular apertures, 45 and a connection between the shank and body consisting of a nut interiorly threaded to coöperate with the shank and two bear-

ings each arranged to seat within both of the apertures formed in the body walls, the bearings being formed also to receive the 50 shank through each of them and lugs on said bearings to be received within the nut, the shank serving as the sole medium for retaining the bearings and nut in operative relation within the body, substantially as described. 55

3. A wrench having a hollow body two of whose opposite walls are formed with circular apertures each reinforced with an outwardly turned flange, a pair of bearings seated within both openings and freely rotatable therein and removable therefrom, a nut arranged between the bearings, there being means projecting from each bearing into the nut to preserve these parts in operative relation, and means for holding the nut and its associated bearings operatively within the wrench body consisting of a jaw having a threaded shank with which the nut may coöperate, the shank being extended 65 through the nut and each of its bearings, substantially as described. 70

4. A wrench having a jaw with rectangular shank threaded on its narrower sides, a nut interiorly threaded to coöperate with the shank, two bearings for the nut, one at each end thereof, and each provided with a lug adapted to enter within the nut adjacent a wider side of the shank, and each slotted to receive therethrough the shank of the jaw, and a body for the wrench having spaced walls between which the shank may be received, there being registering apertures in the walls within both of which the bearings may lie, the engaging surfaces of the 80 bearings and walls surrounding the aperture being circular whereby the shank may be tilted forwardly and backwardly around an axis which is coincident with the center of each aperture, substantially as described. 85 90

DENIS O'CONNOR.
